UNITED STATES PATENT OFFICE.

WILLIAM M. HAMILTON, OF CONEY ISLAND, NEW YORK.

GAME APPARATUS.

Application filed October 28, 1922. Serial No. 597,446.

To all whom it may concern:

Be it known that I, WILLIAM M. HAMILTON, a citizen of the United States, residing at Coney Island, in the county of Kings and State of New York, have invented certain new and useful Improvements in Game Apparatus, of which the following is a specification.

My invention relates to game apparatus and its object is to provide means for playing a game requiring skill and judgment and which may be played by an individual or by two or more individuals playing competitively.

This object, and other advantageous ends which will be described hereinafter, I attain in the following manner reference being had to the accompanying drawings in which—

Figure 1 is a perspective view of the exterior of a game apparatus embodying my invention,

Figure 2 a vertical section on line 2—2 of Figure 1,

Figure 3 a section on line 3—3 of Figure 2,

Figure 4 a section on line 4—4 of Figure 3,

Figure 5 a fragmentary elevation, partly in section, showing the coin slot and coin releasing mechanism,

Figure 6 a section on line 6—6 of Figure 3 showing an insulated unit,

Figure 7 a vertical perspective section of a score indicating compartment,

Figure 8 a central section through the controlling mechanism or inertia switch,

Figure 9 a section substantially on line 9—9 of Figure 8 showing the switch box partly broken away,

Figure 10 a section on line 10—10 of Figure 9 but showing the switch carriage in full,

Figure 11 a top plan view of the operating mechanism,

Figure 12 a side elevation of the same, and

Figure 13 a diagrammatic view showing the electric connections.

The numeral 1 indicates a cabinet which encloses most of the mechanism. As shown the cabinet encloses four units which are of identical construction. The cabinet, in the form shown, has a flat upper face 2 through

which switch levers 3 project, an inclined upper face 4 provided with coin slots 5, 55 there being a slot for each unit, a second inclined upper face 6, separated from inclined face 4 by a shoulder 7, and a series of score indicating compartments 8 at its upper rear having transparent faces 9, one for each 60 unit. The inclined face 6 is of non-magnetic material and provided with series of defined spaces, one series for each unit. The upper and lower boundaries of these spaces are marked for scoring and the scoring 65 marks are indicated by numerals 5 and 20 alternated with each other, each series having 4 scoring marks 5 and 4 scoring marks 20 so that the total score for each series is 100. A movable object, such as a cylinder 70 10, normally rests upon the shoulder 7 at the foot of each series of spaces, and the game is played by mechanically imparting motion to the cylinder, the object being to cause it to move upward along the incline, 75 step by step, in such manner that it will come to rest on each numbered line consecutively, the score for each line being indicated in a score indicating compartment. If the player succeeds in so projecting the cylinder 75 that it comes to rest consecutively upon each scoring mark of the series he gets a score of 100. If he so projects the cylinder that it jumps one or more marks without resting thereon, those marks do not count. 85

The operating mechanism includes a motor 11, a gear wheel 12 on the motor shaft meshing with a gear wheel 13 fixed to a shaft 14 carrying a worm 15 which meshes with a toothed wheel 16 fixed to a 90 shaft 17 having its bearing in a bracket. Shaft 17 carries a crank arm 18 pivotally connected to a rack bar 19 which engages with a toothed wheel 20 mounted on a shaft 21 having a drive pulley 22 fixed thereto. 95 A cable 23 leads over pulley 22, guide pulleys 24 and 25 and a pulley 26, guide pulley 24 and pulley 26 being disposed under and adjacent to the inclined face 6, the guide pulley 24 being adjacent the top of the inclined face and pulley 26 below the lower end thereof. Cable 23 is intercepted by carriages 27 and 28 which travel in tracks 29 and 30 in a housing 31 which encloses guide pulleys 24 and 25 and pulley 26. Carriage 105 28 serves as a counterweight to balance car-

riage 27. Carriage 27 carries a magnet 32 and is provided at an upper corner with a wheel 33 of fibre, or other non-conducting material, the other wheel 34 being of conducting material. Housing 31 carries a series of electric contacts 35 separated from track 29 and housing 30 by a block of insulating material 36 spaced to correspond with the scoring marks on inclined face 6 and each electrically connected with a signal lamp. These contacts are arranged in the path of travel of the non-conducting wheel and the conducting wheel on the same side of the carriage so that upon contact of the conducting wheel with a contact point 35 an electric circuit through the carriage may be completed.

The cylinder projecting mechanism, which will hereinafter be called the inertia switch, is shown in Figures 8 to 10 of the drawings in which 37 indicates a carriage so mounted that it may be reciprocated on rails 38 by means of a switch lever 3, pivoted at 39 and taking through a slot 40 in the rail base and a slot in the carriage indicated at 41; the latter slot being preferably provided at its ends with resilient cushion rolls 42. Two frames 43 and 44 of non-conducting material are arranged longitudinally of the carriage; frame 43 being hinged to the carriage, adjacent one end, at 45 and frame 44 hinged adjacent the other end at 46. The free ends of the frames rest upon the heads of adjusting screws 47 whereby the frames may be adjusted to incline at any desired angle from the horizontal. Each frame carries two longitudinally extending rods each of which is composed of a section 48 of electrically conducting material and a section 49 of non-conducting material, the latter section being adjacent the hinged end of the frame. The conducting sections are preferably made of, or coated with, non-corrosive material and the rods rotatably mounted so that they may be turned to provide different lines of contact. A ball 50 of conducting material is placed on each pair of rods, which serve as a track therefor, and normally rests upon the non-conducting sections of the rods and against the lower end of the frame. Each frame is provided with terminals 51 which are in circuit with the motor. One end of each carriage is provided with an electric contact 52 adapted to engage a contact 53 on the housing and in circuit with the motor. Coiled springs 54 normally hold the switch lever in its central or idle position.

Beneath each of the coin slots 5 is a switch composed of a guide way consisting of a fixed plate 55 and a pivoted bent arm 56 the bent end of which is connected by a link 57 with a cross arm 58 pivoted to the housing at 59. One end of the cross arm is positioned to engage with a shoulder 60 on

the magnet carriage when that carriage is in its low position and the other end positioned to engage with a shoulder 61 on the counterbalance carriage when that is in its low position. Plate 55, bent arm 56, link 57 and cross arm 58 constitute a switch, hereinafter called the coin switch.

Plate 55 and arm 56 which are insulated from the housing, are in circuit with the motor and serve as contacts. Link 57 is of fibre or other non-metallic material. When the mechanism is idle arm 56 slopes toward plate 55 and is held in such a position that a coin dropped through the coin slot will be engaged and held between the movable arm and the plate until the arm is withdrawn by some force other than the pressure exerted by the coin. An insulated terminal 62, in circuit with the motor, is so mounted as to be engaged by arm 56 when the latter is swung to permit passage of a coin.

A governor switch 63, of centrifugal type is mounted upon a spindle 64 having its bearings in brackets 65 and carrying a pulley 66 which is connected by a belt 67 with a pulley 68 on the motor shaft, the arrangement being such that, while the motor shaft is revolving, the switch is open but is closed when the rotation of the motor shaft, and consequently that of the governor spindle, stops.

The rack operating mechanism is so proportioned and the magnet carriage and counterbalance carriage so positioned in the length of the cable that actuation of the rack bar 19 through one complete stroke, will cause the magnet carriage to move upwardly the full length of the incline, and a reverse stroke of the rack bar will cause the magnet carriage to move downwardly and the counter-balance carriage to move upwardly the full length of the incline.

When a coin is placed in the slot electrical connection is established between one terminal of the inertia switch, the motor, the battery and the other terminal of the inertia switch. By imparting movement to the switch lever 3 ball 50 may be projected upwardly on rods 47. When the ball reaches the conducting sections of the rods electrical connection is established between the rods, a circuit is completed between the switch and the motor, the motor is set in motion and will continue in motion so long, and so long only, as the ball remains upon the conducting parts of the rods. Action of the motor will cause movement of the rack bar, the cable, the magnet carriage and the counterbalance carriage, and the extent of these movements will be proportioned to the time the motor is in action. Movement of the magnet will impart a concurrent movement to the visible cylinder 10.

When the magnet carriage comes to rest,

and its wheel 34 is in contact with one of the contact points 35, stopping of the motor will cause the governor switch to close a circuit through a relay 69 and cut in a shunt circuit to light a signal lamp 70 which will disclose a number, either 5 or 20, corresponding to the position cylinder 10 occupies on the inclined face 6. The shunt circuit keeps the relay energized when the magnet carriage leaves contacts 35. A second movement of the switch lever will cause like action and this will be repeated until the magnet carriage reaches the limit of its upward travel. Shoulder 61 on the counterbalance carriage will then engage with and retract cross arm 57 thereby allowing the coin to drop and breaking the connection between the motor and the inertia switch. This will bring cross arm 58 into contact with contact point 66 which is in electrical connection with the motor and complete a circuit through the motor thereby causing a reverse motion of the rack bar 19. The motor will continue in operation until the reverse movement of the rack bar is completed and the magnet carriage reaches the limit of its downward travel. Shoulder 60 on the carriage will then engage with cross arm 58, break the circuit through the motor and restore arm 56 to position for engagement with a coin.

In use, a slight movement of a switch lever is sufficient to cause the magnet and cylinder to move one step, but a like result may be obtained by an abrupt movement of the lever to the limit of its travel. This will cause a very rapid movement of ball 50 and a quick return so that its contact with the rods is brief and the motion imparted to the magnet correspondingly limited. Such abrupt action places unnecessary strains upon the machine and players are apt to prefer the rough rather than the gentle movement. To guard against such practice I provide the terminals 51 and 52 so placed that when the switch carriage approaches the limit of its travel these contacts will engage and a circuit will be completed through the motor. This will cause operation of the motor long enough to insure a greater movement of the magnet than is desired and thereby discourage forceful use of the switch lever.

The inertia switch, the coin slot switch and the motor are in an electric circuit including a battery. To close this circuit a coin must be dropped in the slot and the inertia switch manipulated. The magnet carriage is in a circuit including the governor switch, the battery and a relay circuit including a shunt circuit having a signal lamp. To close this circuit the governor switch must be closed and the magnet carriage must be in electrical contact

with one of the contact terminals 35. When the relay magnet is energized the signal lamp retains its illumination until the circuit is broken by the operator.

While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:—

1. A casing having a non-magnetic face, marked for scoring; a magnet adapted for travel under the face; means for supporting the magnet; an object adapted to be attracted and moved by the magnet above the face to make a score; means for causing the magnet to travel; score-indicating means, and means operatively connected with the magnet supporting means for actuating the score-indicating means to indicate the score.

2. A casing having a non-magnetic face, marked for scoring; a magnet adapted for travel under the face; means for supporting the magnet; an object adapted to be attracted and moved by the magnet above the face to make a score; manually operated means for causing the magnet to travel distances dependent upon the manipulation of the manually operated means; score-indicating means, and means operatively connected with the magnet supporting means for actuating the score-indicating means to indicate the score.

3. A casing having a non-magnetic face, marked for scoring; a magnet adapted for travel under the face; means for supporting the magnet; an object adapted to be attracted and moved by the magnet above the face to make a score; operating means for causing the magnet to travel and stop; means for retaining the magnet in an acquired position until the operating means is again actuated; score-indicating means, and means operatively connected with the magnet supporting means for actuating the score-indicating means to indicate the score.

4. A casing having a non-magnetic face, marked for scoring; a magnet adapted for travel under the face; means for supporting the magnet; an object adapted to be attracted and moved by the magnet above the face to make a score; manually operated means for causing the magnet to travel distances dependent upon the manipulation of the manually operated means; means for retaining the magnet in an acquired position

until the manually operated means are again actuated; score indicating means, and means operatively connected with the magnet supporting means for actuating the score indicating means to indicate the score.

5. A casing having a non-magnetic face, marked for scoring; a magnet adapted for travel under the face; means for supporting the magnet; an object adapted to be attracted and moved by the magnet above the face to make a score; manually operated means for causing the magnet to travel distances dependent upon the manipulation of the manually operated means, and automatic means for returning the magnet to its supporting position when it reaches the limit or its forward travel.

6. A casing having a non-magnetic face, marked for scoring; a magnet adapted for travel under the face; means for supporting the magnet; an object adapted to be attracted and moved by the magnet above the face to make a score; a lever; means operatively connected with the lever for causing the magnet to travel distances dependent upon the manipulation of the lever; score indicating means, and means operatively connected with the magnet supporting means for actuating the score indicating means to indicate the score.

7. A casing having a non-magnetic face, marked for scoring; tracks on the casing under the face; a carriage adapted to travel on the tracks; a magnet on the carriage; an object on the face adapted to be attracted and moved by the magnet; score indicating means, and means operatively connected with the magnet supporting means for actuating the score indicating means to indicate the score.

8. A casing having a non-magnetic face, marked for scoring; tracks on the casing under the face, one of the tracks being insulated and provided with insulated contacts spaced to correspond with the scoring marks; a carriage adapted to travel on the tracks; a magnet on the carriage; a magnetic object on the face adapted to be moved by the magnet; means for imparting motion to the carriage, and scoring means connected with the contacts, operative to indicate the score when the magnetic object stops on a scoring mark.

9. A casing having a non-magnetic face, marked for scoring; a magnetic object movable thereon; a magnet under the face adapted to attract the object; tracks on the casing, one track being insulated; electric contacts upon the insulated track spaced to correspond with the scoring marks; relay circuits having one end connected with the contacts and the other end grounded to the non-insulated track; a governor switch in the relay circuits; a circuit shunting the relay circuits; a scoring indicating device

therein; a carriage supporting the magnet adapted to travel on the tracks and to close a relay circuit when it stops on a contact; a motor for moving the carriage, and connections between the motor and the governor switch whereby the switch will be closed when the motor stops.

10. A casing having a non-magnetic face; a magnetic object movable thereon; a magnet under the face adapted to attract the object; a carriage for the magnet; a motor for imparting motion to the carriage; means operatively connected to the motor for reversing the movement of the carriage; controlling means for causing intermittent movement of the motor during the forward movement of the magnet, and automatically operative means for causing continuous movement of the motor during the reverse movement of the magnet.

11. A casing having a non-magnetic face; a magnetic object movable thereon; a magnet under the face adapted to attract the object; a carriage for the magnet; a motor for imparting movement to the carriage; means operatively connected to the motor for reversing the movement of the carriage; a motor circuit; a coin slot switch in series therewith; a manually operated self-opening switch in series therewith, and means for automatically opening the coin slot switch and shunting the manually operated switch when the magnet reaches the limit of its forward travel.

12. A casing having an inclined non-magnetic face; a magnetic object movable thereon; a magnet under the face adapted to attract the object; tracks on the casing; supporting means for the magnet adapted to travel on one set of tracks; a counter-weight adapted to travel on the other set of tracks; guide pulleys mounted in the casing; a drive pulley; a cable connecting the supporting means to the counter-weight and passing over the guide and drive pulleys; a motor for imparting motion to the carriage; connections between the drive pulley and motor for imparting reverse movement to the drive pulley; controlling means for causing intermittent movement of the motor during upward movement of the magnet, and automatically operative means for causing continuous movement of the motor during the reverse movement of the magnet.

13. A casing having a non-magnetic face marked for scoring; tracks disposed below the face; a carriage carrying a magnet and adapted for travel on the tracks; manually operated means for causing the carriage to travel distances dependent upon the manipulation of the operating means, and contact terminals mounted in the path of travel of the carriage, and spaced to correspond with the scoring marks; relay circuits including signal lamps, and electric connections, be-

tween the relay circuits, carriage and each contact terminal, whereby a relay circuit may be energized.

14. A casing having a non-magnetic face marked for scoring; tracks disposed beneath the face; a carriage; a magnet carried by the carriage; an electric motor; connections between the motor and the carriage whereby motion may be imparted to the carriage; contact terminals mounted in the path of travel of the carriage and spaced to correspond with the scoring marks on the face; shunt circuits including signal lamps; a relay circuit, including the magnet carriage and the contact terminals, whereby the relays may be energized, and a governor switch, connected with the motor, arranged to hold the relay circuit broken while the motor rotates and close the relay circuit when the motor is stopped and the magnet carriage is in contact with a terminal.

15. A casing having a non-magnetic face marked for scoring; tracks disposed below the face; a carriage carrying a magnet and adapted for travel on the tracks; a cable connected with the carriage; a pulley adapted to impart motion to the cable; an electric motor; connections between the motor and the pulley whereby operation of the motor causes movement of the pulley and cable, and a manually closed automatically opening switch in circuit with the motor whereby the circuit may be temporarily closed and the motor temporarily operated.

35 16. A casing having a non-magnetic face; a magnet adapted for travel beneath the face; a carriage for the magnet; an electric motor; connections between the motor and the magnet carriage whereby the latter may be caused to travel, and an inertia switch, in circuit with the motor, consisting of a switch carriage, an insulated compartment mounted longitudinally of the switch carriage, a pair of rods extending longitudinally of the compartment and having a non-conducting and conducting section, an electrically conducting ball normally resting upon the non-conducting sections, and means for imparting motion to the switch carriage whereby a ball may be projected onto the conducting sections and thereby close the circuit.

17. A casing having a non-magnetic face; a magnet adapted for travel beneath the face; a carriage for the magnet; an electric motor; connections between the motor and the magnet carriage whereby the latter may be caused to travel; an inertia switch in circuit with the motor, consisting of a switch carriage, an insulated compartment mounted longitudinally of the switch carriage and having a non-conducting and conducting section; and electrically conducting ball normally resting upon the non-conducting sections; means for im-

parting motion to the switch carriage whereby the ball may be projected onto the conducting sections thereby closing the circuit; a contact terminal on the casing in circuit with the motor, and a contact terminal on the end of the switch carriage adapted to engage the terminal on the casing when the switch carriage reaches its limit of travel thereby closing a circuit through the motor.

18. A casing having an inclined non-magnetic face marked for scoring; an electric motor, a cable adapted to be driven thereby; a carriage adapted to travel beneath the inclined face and connected with the cable; a magnet carried thereby; a counterbalance carriage connected with the cable; a fixed contact plate and a movable contact plate disposed beneath a coin slot and in circuit with the motor, the contact plates being adapted to receive and hold a coin; an arm pivotally mounted in the casing and adapted to be actuated, in one direction, by the counterbalance carriage when it reaches the limit of its downward travel and, in the other direction by the magnet carriage when it reaches the limit of its downward travel, and connections between the movable contact plate and the pivoted arm whereby the counterbalance carriage actuates the arm to withdraw the movable plate and close a circuit through the motor and the magnet carriage actuates the pivoted arm to restore the movable contact plate to its normal position and breaks the circuit through the motor.

19. A casing having a non-magnetic face marked for scoring; tracks disposed beneath the inclined face; a carriage adapted for travel on the tracks; a magnet carried by the carriage; a cable arranged for travel on pulleys disposed at the top and bottom of the inclined face; a pulley adapted to drive the cable; a spur gear fixed thereto; an electric motor; a worm shaft adapted to be driven thereby; a spur gear meshing with the worm shaft; a crank arm carried thereby; a rack bar connected with the crank arm and meshing with the spur gear on the driving pulley, and means, in circuit with the motor, for variably closing the circuit thereby causing motion of the magnet carriage.

20. A casing having a non-magnetic face, marked for scoring; a plurality of magnets adapted for travel under the face; movable supports for the magnets; a plurality of objects, one for each magnet, adapted to be attracted and moved by the magnet on the face to make a score; a motor having connections whereby motion may be imparted to the magnetic supports; manually operated means, having electrical connections with the motor whereby the motor may be caused to rotate and to cause

the individual magnetic supports to travel distances dependent upon the manipulation of the manually operated means; score indicating means, and means operatively connected with the magnet supports for actuating the score indicating means to indicate the score.

In testimony whereof I have signed my name to this specification in the presence of two subscribing witnesses.

WILLIAM M. HAMILTON.
